UNITED STATES PATENT OFFICE.

FREDERICK J. CASWELL AND CLARENCE C. WOOD, OF WOODVILLE,
MASSACHUSETTS.

TROLLEY-HARP.

SPECIFICATION forming part of Letters Patent No. 717,542, dated January 6, 1903.

Application filed February 10, 1902. Serial No. 93,340. (No model.)

To all whom it may concern:

Be it known that we, FREDERICK J. CASWELL and CLARENCE C. WOOD, citizens of the United States, and residents of Woodville, 5 in the county of Middlesex and State of Massachusetts, have invented a new and Improved Trolley-Harp, of which the following is a full, clear, and exact description.

The object of this invention is to insure the proper engagement of the trolley with the wire, notwithstanding that the course may be 10 devious and the road irregular; and it comprises certain novel features involving a spring-sustained trolley, which will be fully 15 explained hereinafter and pointed out in the claims.

This specification is an exact description of one example of our invention, while the claims define the actual scope thereof.

Reference is to be had to the accompanying drawings, forming a part of this specification, in which similar characters of reference indicate corresponding parts in all the views.

Figure 1 is a perspective view of the invention. Fig. 2 is a section on the line 2-2 of Fig. 1, and Fig. 3 is a plan view.

a represents the trolley-pole, and b the end extension thereof, which is provided with a reduced part b', (see Fig. 3,) secured in a cavity formed in the pole. The upper end of the extension b is turned laterally to form a holder b², and below this holder is arranged a laterally-projecting arm b³, carried by the extension b.

c indicates a brace extending between the arm b³ and the pole a, so as firmly to hold the parts a and b engaged and also to brace the arm b³.

d indicates the trolley-wheel, and d' the cheek-plates thereof. Fastened to the plates or shell d' is a shank e, which projects downward and is fitted to slide vertically in the holder b². This shank has a reduced portion e', projecting below the holder b² and extending

down to an eye in the outer end of the arm b³, these parts e and e' being loosely engaged with the parts b² and b³. As shown best in Fig. 2, the lower end of the shank e is provided with a transverse key e², which engages under the holder b² to prevent upward movement of the parts above the position

shown in Fig. 1, and f indicates an expansive spring, which is placed around the reduced part e' of the shank, this spring bearing against the lower end of the main part e of the shank and the arm b³. (See Fig. 2.) The spring f therefore serves to hold the parts 55 yieldingly in the position shown in Figs. 1 and 2; but the shank e and its reduced extension e' may move downward relatively to the parts b² and b³ until the cheeks or shell d' of the trolley-wheel strike the holder b².

Fastened to the cheeks d' at each side of the trolley-wheel and projecting forwardly are downwardly-curved arms g, which extend 65 down to the extension b of the pole and lie one on each side thereof, the lower ends of the arms g being turned in toward each other, as indicated at g'. These arms g allow the trolley-wheel with its attached shank limited 70 turning movement on the pole; but this movement is not great enough to impair the proper engagement of the trolley-wheel with the wire, while at the same time it allows for freedom of movement necessary for the trolley- 75 wheel in turning curves and other irregular portions of the road.

The use of the invention will be apparent from the illustration and the foregoing description, and it will be seen that by means 80 of the construction employed the trolley-wheel is allowed to move freely within the necessary scope and that other movements are effectively prevented. The arms g also prevent the trolley-harp from catching against 85 crossing wires, brackets, and other obstructions, since owing to their peculiar form the whole device is caused easily to ride under the obstructions.

Various changes in the form and details of 90 our invention may be resorted to at will without departing from the spirit of our invention. Hence we consider ourselves entitled to all forms of the invention as may lie within the intent of our claims.

Having thus described our invention, we claim as new and desire to secure by Letters Patent—

1. The combination of a trolley-pole having holding devices, a trolley, a shank carrying the trolley, the shank being movably mounted in the holding devices, a spring bear-

ing between the holding devices and the shank, and guards sustained from the shank and located one at each side of the trolley, said guards extending forward and downward 5 and lying one on each side of the pole.

2. The combination with the trolley-pole, of a trolley comprising cheek-plates, means for mounting the trolley on the pole, said means being arranged to turn on the pole, 10 and two guards connected with said cheek-plates of the trolley and located one on each side of the trolley, said guards extending forwardly to opposite sides of the pole, for the purpose specified.

15 3. The combination of a trolley-pole having a laterally-projected arm located near the

end of the pole, a holder located at the end of the pole, a shank slidably fitted in the holder and in the arm, a spring yieldingly supporting the shank, a trolley carried by the 20 shank, and a guard sustained on the trolley and extending forwardly past one side of the pole, for the purpose specified.

In testimony whereof we have signed our names to this specification in the presence of 25 two subscribing witnesses.

FREDERICK J. CASWELL.
CLARENCE C. WOOD.
